UNITED STATES PATENT OFFICE.

HERMAN B. LERMER, OF NEWARK, NEW JERSEY, ASSIGNOR TO HYGIENIC TUBE CO., OF NEWARK, NEW JERSEY, A CORPORATION OF NEW JERSEY.

COLLAPSIBLE-TUBE-CLOSING APPARATUS.

Application filed February 12, 1925. Serial No. 8,616.

To all whom it may concern:

Be it known that I, HERMAN B. LERMER, a citizen of the United States, residing in Newark, in the county of Essex and State of New Jersey, have invented new and useful Improvements in Collapsible-Tube-Closing Apparatus, of which the following is a specification.

This invention relates to apparatus for folding, flattening and fastening the seam at the rear or base end of collapsible tubes and has as its main object to provide a simple hand operated device for folding the juxtaposed edges of a tube to form an elongated bight at one operation, the device being further provided with means whereby, at a second operation, the fold may be flattened to produce a hermetically closed joint or seam.

A further feature is in the provision of means for performing the dual operation, of folding and flattening in a single apparatus, in producing a neat appearing and effective closure, in a practical and rapid manner and with a moderate expenditure of physical effort.

These and other important aims and objects are attained by the novel construction, combination and arrangement of parts hereinafter described and shown in the annexed drawing, constituting an essential portion of this disclosure and in which:—

Figure 1 is a front elevational view of an embodiment of the invention, ready for operation.

Figure 2 is a side elevational view of the same.

Figure 3 is a partial sectional, partial plan view thereof, the section being taken on line 3—3 of Figure 2.

Figure 4 is an enlarged transverse sectional view taken on line 4—4 of Figure 1.

Figure 5 is a similar sectional view taken on line 5—5 of Figure 3.

Figure 6 is a diagrammatic view illustrating the first operation in seaming a collapsible tube.

Figure 7 is a similar view of the second operation, showing the tube end as folded as indicated in Figure 4.

Figure 8 is another like view showing the tube end as completed.

Referring to the drawing in greater detail, the numeral 10 designates a stand base, from which rises a column 11, curved at

its upper end towards the front and blended into a vertical cylindrical guide 12 split longitudinally at the front and having pairs of lugs 13 adapted to receive clamp screws 14 by which the bore of the guide 12 may be slightly adjusted to compensate for wear.

A plunger 15 is slidably mounted in the guide, its upper end being finished convexly, as at 16, and passing through the upper portion of the plunger is a pin 17 acting to receive the thrust of a coiled compression spring 18 resting on the top of the guide, encircling the plunger and exerting pressure to raise the same.

A pair of lugs 19 extend upward from the column 11, above and rearward of the guide 12, and mounted between the lugs is a handle lever 20, pivoted on a pin 21 and having a curved, forwardly extending portion 22 disposed in such manner as to engage the curved end 16 of the plunger and depress the same when the lever is raised.

The base 10 is provided with opening 23 through which may be passed screws or equivalent fastening to secure the stand 80 rigidly upon a support.

At the front of the base 10 is a block 85 extending across from side to side and held in fixed position by screws 25 passed up through the base as shown.

This block is a parallelogram in shape, having a level upper surface and bevelled at its front upper corner as at 26, the left hand portion being rounded as at 27, thus blending the upper surface and angular edge 90 smoothly.

On the right hand side of the block is a longitudinal groove 28, having slightly converging sides and being smoothly finished, the other side of the block being smooth and level as at 29, presenting an anvil surface.

Stops 30 are held to the ends of the block by screws 31, alining with the groove 28 and surface 29 respectively, and rearward of the groove and surface are guide strips 32 and 33 having transverse slots through which pass clamp screws 34 permitting individual adjustment relative to the front of the block.

Fixed centrally in the lower end of the plunger is a flat rectangular bar 35 substantially equivalent in length with the block 24, one of the lower level edges 36 being adapted to make contact with the surface 29 at the left hand portion of the block, and the right hand portion of the block is formed 110

to present a relatively narrow edge 37, extending below the surface 36 and adapted to enter the groove 28 upon actuation of the lever 20.

6. In operation, the plunger 15 being held by the spring to retain the bar 35 in a raised position, a filled collapsible tube 40 is held by hand so that its end 41 closed by flattening, makes contact with the guide 32 over the 10 groove 28, the stop 30 assuring the correct position of the tube.

When the tube is thus positioned the hand lever 20 is operated, forcing the bar element 37 downward and, as shown in Figure 4, 15 forming a transverse indentation entirely across the end of the tube and effecting the first operation in folding, the tube assuming the shape shown in Figure 7.

The second operation is performed by 20 moving the tube 40 to the left over the anvil surface 29, again actuating the hand lever, bringing the hammer element 36 forcibly downward, as in Figure 5, closing the seam and completing the closing operation, the 25 finished tube appearing in Figure 8.

It is also to be noted that a clasp or clip 42 of generally U shaped cross section, is shown in Figures 6, 7 and 8, as applied over the flattened and closed end of the tube, the clip 30 being of thin yielding sheet material, as aluminum, making close contact with the walls of the tube, acting as a re-enforcement and clamp for the same, the clip being bent lengthwise over the tube, in the manner indicated, affording a firm and secure closure, 35 preventing the possibility of air or moisture leakage.

Although the foregoing is descriptive of the preferred embodiment of the invention, 40 minor changes may be made in its construction without conflicting with the scope of the claims hereto appended.

Having thus described my invention, what 45 I claim as new and desire to secure by Letters Patent, is:—

1. A portable seaming apparatus for closing collapsible tube ends comprising a stand, a spring supported plunger slidable therein, a die block on said stand, said block having a 50 narrow longitudinal groove, a bar carried by said plunger to indent the tube end by pressing it into the groove, and a manually operable lever to actuate said plunger.

2. A portable seaming apparatus for closing collapsible tube ends comprising a stand, a spring supported plunger slidable therein, a die block on said stand, said block having a narrow longitudinal groove in one por-

tion thereof and a level surface on an adjacent portion, a horizontal bar carried by said plunger, said bar having a part adapted to enter the groove in said block and another part to make contact with the level surface thereof, and a hand lever for directly actuating said plunger.

3. A portable seaming apparatus for closing collapsible tube ends comprising a stand, a plunger slidable therein, a die block on said stand, said block having a narrow longitudinal groove in one portion thereof and a level surface on an adjacent portion, the front edge of said block being bevelled throughout the length and curved to blend with the level upper surface, a horizontal bar carried by said plunger, said bar having a 50 part adapted to enter the groove in said block and another part to make contact with the level surface thereof, independent means adjustable on said block to guide a tube in register with the groove and for adjusting a tube upon the level portion of said block, a spring normally raising said plunger, and manual means for depressing the plunger.

4. A portable seaming apparatus for indenting and folding collapsible tube ends comprising upper and lower dies arranged in pairs, one of the pairs presenting respectively tongue and groove formation adapted to indent and initially fold the flattened end of a tube, and the other pair presenting flat surfaces to flatten and finish the fold, and a single means for actuating said upper dies.

5. A portable apparatus for sealing collapsible tubes having flattened ends enveloped in clasps, comprising a stationary stand having a die block on its upper surface, a plunger slidably mounted in said stand, said plunger being normally spring pressed away from said block, a hand lever to depress said plunger, a die bar fixed to the plunger to extend over the block, an anvil surface on one side of said block, a longitudinal groove in the other side thereof, said block having a bevelled front edge a hammer element on said bar to contact with the anvil surface, a projecting die member on said bar cooperative with the groove to produce a transverse fold in the end of a tube and its clasp, the fold thus produced being flattened between the hammer and anvil surface and independently adjustable gages for each operation.

This specification signed this 10th day of February, 1925.

HERMAN B. LERMER.
